HATRACK

Harold T. Cook, Seattle, Wash., assignor of one-half to Alfred G. Schnee, Seattle, Wash.

Application May 15, 1950, Serial No. 9,939

Term of patent 7 years

(Cl. D33—8)

To all whom it may concern:

Be it known that I, Harold T. Cook, a citizen of the United States, residing at Seattle, King County, State of Washington, have invented a new, original, and ornamental Design for a Hatrack, of which the following is a specification, reference being had to the accompanying drawing, forming a part hereof.

Figure 1 is a perspective view showing my ornamental design for a hatrack.

Figure 2 is a front view of the same.

Figure 3 is a side view of the same, the broken line representing an upright supporting surface upon which such a hatrack may be mounted and being for illustrative purposes only.

I claim:

The ornamental design for a hatrack, as shown and described.

HAROLD T. COOK.
